UNITED STATES PATENT OFFICE.

HARRY J. BOSWORTH, OF CHICAGO, ILLINOIS, ASSIGNOR TO HARRY J. BOSWORTH COMPANY, A CORPORATION OF ILLINOIS.

DENTAL BURNER.

Application filed November 28, 1927. Serial No. 236,034.

This invention relates to burners, more particularly to dental burners and it may be characterized as an improvement on the dental burner illustrated and described in

5 United States Letters Patent No. 1,536,079, granted May 5, 1925, to Ernest E. Dalton.

The burner of the present invention is particularly adapted for removing the wax or other casting and sprue cavity forming

10 material from dental casting cases or investments and the object of the present invention is the provision of a generally improved and simplified device and more particularly a device having a wider range of

15 heat application and adapted for more uniformly distributing the heat over the height of the casting case or investment. The present burner is adapted for more expeditiously handling investments or casting cases of

20 greater height and is adapted for burning out the wax or other sprue and casting cavity forming material quickly and thoroughly.

According to the present invention I provide a pair of burner rings, each having a plurality of inwardly opening and generally radially directed burner jets or orifices for projecting the flames radially inwardly in substantially the planes of the rings and another object is the provision of an im- 30 proved adjustable supporting arrangement for these burner rings by means of which the relative vertical positions of the rings may be conveniently adjusted.

A further object is the provision of an improved balanced supporting arrangement for the adjustable casting case or investment supporting means.

The invention is illustrated in the accompanying drawing in which:

40 Fig. 1 is a plan view of a dental burner embodying the present invention;

Fig. 2 is a vertical section taken on the line 2—2 of Fig. 1; and

45 Fig. 3 is a detail horizontal section taken on the line 3—3 of Fig. 2.

Referring to the drawing, the device shown comprises a base 5, having a pair of diametrically opposite hollow upright posts or standards 6 and 7. The upper surface of the base 5 is shown as raised at 8 and provided with a peripheral supporting flange 9 and the lower ends of the posts 6 and 7 are closed and secured upon the top of the base 5 as by means of screws 10.

50 Each of the hollow posts 6 and 7 is pro-

vided with a nipple 12 for receiving the ends of the gas or other fuel supply hose connections and for delivering the gas or other fuel from these connections into the hollow interiors of the posts 6 and 7. Each post 6 and 7 is provided with a plurality of radially opening air ports 13, opening in around its polygonal sides, as shown in Fig. 3, for admitting air into the stream of gas flowing up through the respective burner rings. 65

The upper burner ring 15 comprises a tube of wrought metal or other suitable material bent or formed into the horizontal circular loop or ring 15. One end of this tube is closed at 16 as by pressing the walls thereof together, or by soldering or plugging the end of the tube in any suitable or preferred manner. The opposite end of the tube is turned down substantially vertically at 18 and is telescopically engaged at its lower 70 end in the upwardly opening internal bore 19 of the supporting and gas supply post 7. The lower end of the upright tube portion 18 has sliding adjustment in the post 7 to adjust the vertical position of the burner 80 ring 15 and the lower end of this upright tube portion is secured in adjusted position in the post 7 by means of a thumb screw 20. It is to be understood that the sliding fit of the tube in the post 7 may, if desired, be 85 packed as an additional precaution against gas leakage, although we have not found this necessary. It is also to be understood that while the lower end of the upright tube portion 18 is adjustable in the post 7, the adjustment which is permitted is that between the top of the air ports 13 and the thumb screw 20 as the air ports 13 must be positioned below the lower end of the tube 18 in all 90 positions of adjustment of the ring 15. 95

The lower burner ring 25 comprises a tube bent or formed into the horizontal circular loop or ring 25 with one end of the tube closed at 26 similarly to the tube 15 and the other end turned down at 28 and telescopically engaged at its lower end in the supporting and gas supply post 6. The lower end of the upright tube portion 28 is adjustable in the upwardly opening bore 30 of the post 6 similarly to the adjustment of 100 the tube 18 in the post 7 and the tube 28 is similarly secured in adjusted position as by means of a suitable thumb screw 32.

The adjustable support for supporting the casting case, investment or other article to 110

be heated, comprises a block 35 slidably mounted on the vertical portion 28 of the burner ring 25 and a rod bent or formed into a horizontal circular supporting loop 36 or ring 36, with one end turned down at 37 and secured in an opening in the block 35 as by means of a suitable set screw 38. A thumb screw 39 screws through the back of the block 35 into engagement with the vertical tube portion 28 and affords a clamping means for clamping the block 35 to the tube 28 with the supporting ring 36 at any desired height relative to the burner ring 25.

To provide a balanced and improved support for the ring 36 a block 40, similar to the block 35, is slidably mounted on the vertical tube 18 and is similarly clamped to the tube 18 in any desired vertical position as by means of a thumb screw 42. When the supporting ring 36 is adjusted to its desired vertical position on the tube 28, the block 40 is adapted to be moved up into engagement beneath the ring 36 to support the ring diametrically opposite the block 35. At the same time the block 40 is provided with a vertical opening 43 for receiving the down-turned end 37 of the ring 36 and with suitable set screw means 44, so that the ring 36 may be removed from the block 35 and secured in the block 40 above the burner ring 25 and below the burner ring 15, should it be desirable to do so. The block 40 is therefore slidable along the post 18 past the burner ring 25 and in this manner the casting case, investment or other article may be heated from below by the burner ring 25 and around the sides by the burner ring 15.

It is to be understood, of course, that in using the burner, the casting case, investment or other article is placed upon a supporting screen 46 which is in turn placed upon and supported by the ring 36. While a screen is preferable any other suitable supporting sheet or element may of course be employed. The burner rings 15 and 25 are swingable about the axes of the vertical tubes 18 and 28 when the thumb screws 20 and 32 are loosened sufficiently to permit the same and when the thumb screws 39 and 42 are loosened the blocks 35 and 40 may be swung about the vertical tubes 28 and 18, whereas the supporting ring 36 is swingable about its down-turned end 37 when the set screw 38 is loosened sufficiently to permit.

The burner ring 15 has a plurality of radial jets or orifices 50 around its inner circumference, which orifices discharge radially in the plane of the ring 15 and the lower burner ring 25 has a plurality of similar orifices 52 which are similarly directed radially in the plane of the ring 25. By the burner ring and orifice arrangement the advantages of the prior Dalton patent

are secured and by the disposition of the two rings one above the other a wider range of heat application may be secured and at the same time a uniform application of the heat may be provided over a relatively great height. By adjusting the burner rings 15 or 25 relative to each other the vertical range of heat application may be conveniently adjusted and with the supporting arrangement described the supporting ring 36 may be supported at opposite sides and it may be disposed between the burner rings to provide, for example, a soldering heat application beneath the casting case or investment from the ring 25 and a burning out or wax removing heat application over the sides of the casting case or investment from the burner ring 15. There are other uses and advantages of the present burner which will be apparent to those skilled in the art.

I claim:

1. In a device of the character described, the combination of a plurality of superposed burner rings, each of said rings having a plurality of burner jets around its inner circumference, a support for the article to be heated and means for adjusting said rings relative each other.

2. In a device of the character described, the combination of means for supporting an article to be heated, a pair of burner rings adapted to surround the article and each provided with a plurality of burner orifices adapted for discharging substantially radially upon the article, said burner rings having relative vertical adjustment and means for securing same in adjusted position.

3. In a device of the class described, the combination of a pair of burners, means adjustably mounted on one of said burners and adapted for supporting an article to be heated adjacent the burners and means adjustably mounted on the other burner and adapted to be positioned to support said article supporting means adjacent the other burner.

4. In a device of the class described, the combination of a pair of burners, means adjustably mounted on one of said burners and adapted for supporting an article to be heated adjacent said burner, and means adjustably mounted on the other burner and adapted to be positioned to support said article supporting means adjacent the other burner, said last means being adjustable past one of the burners and adapted for supporting the article supporting means between the burners.

5. In combination, a supporting base, a pair of hollow upright gas supply and burner mounting posts on said base, a burner ring having a tubular standard mounted in one of said posts, and a second burner ring underlying said first ring and having a

tubular standard mounted in the other post.

6. In combination, a supporting base, a pair of hollow upright gas supply and burner mounting posts on said base, a burner ring having a tubular standard mounted in one of said posts, and a second burner ring underlying said first ring and having a tubular standard mounted in the other post, said tubular standards opening into said 10 posts and said posts having gas supplying connections and air admission ports.

7. In combination, a supporting base, a pair of hollow upright gas supply and burner mounting posts on said base, a burner 15 ring having a tubular standard mounted in one of said posts, and a second burner ring underlying said first ring and having a tubular standard mounted in the other post, a support for an article to be heated, a member 20 adjustable up and down on said last standard for adjustably supporting said article support beneath both said burner rings and a member adjustable up and down on the other standard for supporting the article 25 support adjacent said other standard.

8. In combination, a supporting base, a pair of hollow upright gas supply and burner mounting posts on said base, a burner ring having a tubular standard mounted in

one of said posts, a second burner ring underlying said first ring and having a tubular standard mounted in the other post, a support for an article to be heated, a member adjustable up and down on said last standard for adjustably supporting said article 30 support beneath both said burner rings and a member adjustable up and down on the other standard for supporting the article support beneath both burner rings adjacent the other standard, said last member being 35 adjustable past the lower burner ring and adapted for supporting the article support between the burner rings.

9. In combination, a supporting base, a hollow upright gas supply and burner 40 mounting post on said base, said post having a gas supply connection and air admission means, a burner ring horizontally disposed and having a plurality of burner orifices 45 discharging radially in substantially the plane of the ring, said burner ring having an upright tubular standard mounted in said post and adjustable above said air admission means and means for securing said standard in adjusted position in said post. 50

In witness whereof, I hereunto subscribe my name this 25th day of November, 1927.

HARRY J. BOSWORTH.
